(57) **CLAIM**

The ornamental design for a plastic bottle for water dispenser, as shown and described.

DESCRIPTION

FIG. 1 is a front elevational view of a plastic bottle for water dispenser showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a perspective view thereof.

The FIG. 5 bottom view is flat. The concentric circles shown on this bottom view are a pattern of lines on this flat surface, having no contour or depth.
